ATTORNEYS

UNITED STATES PATENT OFFICE.

LOUIS H. MORIN, OF NEW YORK, N. Y., ASSIGNOR TO CHESTER PRODUCTS CORPORATION, OF NEW YORK, N. Y., A CORPORATION OF NEW YORK.

STETHOSCOPE.

Application filed December 15, 1924. Serial No. 755,999.

This invention relates to an improvement in stethoscopes, and more particularly to an improvement in the means for connecting the head-piece to the sound tube of the 5 stethoscope.

It is an object of the present invention to provide means for connecting the head-piece and the sound tube of the stethoscope together, which will prevent leakage or escape 10 of the sounds and therefore improve the sound transmission of the stethoscope.

Another object of the invention is to provide a means for connecting and holding the air-tubes of a stethoscope head-piece together, whereby they may be sprung toward each other or drawn apart, to accommodate the head-piece to faces of different widths without inconvenience to the user and without permitting unnecessary escape 20 of the sound waves around the ears.

Another object of the invention is to provide a means for reinforcing the ear tube connecting means.

Various other objects and advantages 25 will appear as the description of the invention proceeds.

Referring now to the drawings, which illustrate a preferred embodiment of the invention,—

30 Fig. 1 is an elevation of the head-piece of a stethoscope showing the sound tube broken away;

Fig. 2 is a bottom plan view of the head-piece, shown in Fig. 1;

35 Fig. 3 is a cross-sectional view of the ear and sound tube connecting means;

Fig. 4 is an elevation of the reinforcing and connecting spring used in my invention; and

40 Fig. 5 is a plan view of the blank from which the spring member is formed.

In the form of the embodiment of the invention illustrated herein, 1 indicates generally a stethoscope head-piece comprising a pair of ear tubes 2, terminating in buttons 3 which fit into the ears of the user. The ear tubes 2 are connected to the sound tube 4, which is preferably a piece of rubber tubing extending to the telephone or other terminus of the stethoscope, by means of a T-shaped connecting member 5, which is preferably constructed of soft rubber.

In the stethoscopes as heretofore constructed, the T-shaped portion 5 has often

been pivoted on the sound tube 4, and the top of the T-shaped portion, being of soft rubber, has not held the ear-pieces 2 firmly in contact with the head of the wearer and has not been adjustable to heads of various widths. In my improved construction of 55 the stethoscope head-piece, I have therefore provided in the T-shaped portion 5, a spring metal reinforcing and connecting member 6, which is provided at each end with a tubular collar 7, which receives and surrounds 60 the ends of the ear tubes 2, the leaf portion 8 of the spring extending between the tubular portions 7 at the top of the T and permitting the soft rubber T-shaped member 5 to be bent by distorting leaf portion 70 8 so as to bring the buttons 3 closer together or farther apart, as the width of the wearer's head may demand. Because of the resiliency and curved contour of section 8 of the spring, there is a tendency to press 75 the buttons 3 resiliently together so as to cause a slight gripping of the head between the buttons, but without sufficient pressure to cause any discomfort or annoyance to the user. The spring member 6 is preferably shaped from a blank 9, stamped from suitable sheet material, and the end portions 9^a are bent around a suitable mandrel to form collars 7. To prevent any escape of 80 the sound in the connection between the sound tube 4 and the connecting member 5, the sound tube 4, which is preferably of a piece of soft rubber tubing, is cemented at 10 to the vertical portion of the T-shaped member 5. In order to prevent collapsing of 85 the inner tube 4 and to secure firm contact of the same with the member 5 when the cement is applied to attach these members together, a short metal ferrule or collar 12 may be inserted in the T-shaped member 5 90 and the end of the sound tube 4 inserted between the collar and the T-shaped member. When the cement is applied, the collar 12 holds the tube 4 in firm contact with the bottom leg of the T-shaped member 5, 100 bringing a firm contact between the inner surface of the T and the sound tube 4 to cause a sound and permanent cementing of 105 these members together to prevent any loss of sound waves at this point.

In assembling the stethoscope head-piece, the spring member 6 is inserted in the mold and the soft rubber connecting member 5

formed around the member 6. The ends of the ear tubes 2 are then inserted in the ends of the T 5 and pushed into the collars 7. A suitable cement 10^a is applied between the rubber of the T-member 5 and the ear tubes 2 to hold the tubes in place, and the sound tube 4 is then connected to the vertical leg of the T in the manner described above.

10 The invention provides an economical method of constructing a head-piece, it provides a head-piece which can be easily adjusted to the head of the wearer and which has sufficient resiliency in the spring 6 to hold the buttons in place in the ears. The cementing of the sound tube 4 to the head-piece and of the ear tubes 2 to the T-shaped portion 5, prevents escape of the sound waves at this point and improves the sound 15 transmission of the stethoscope.

15 Having described my invention, what I claim and desire to secure by Letters Patent is:

1. In a stethoscope head-piece, a pair of ear tubes, a flexible tubular T-shaped member connecting the ear tubes with the sound tube, and means in said T-shaped member for holding the ear tubes in permanently adjusted position.
2. In a stethoscope head-piece, a pair of ear tubes, a sound tube, and an integral 35 tubular flexible T-shaped member connecting the same, stiffening means in said T-shaped member to hold the ear tubes in position, and means for forming a sound proof

connection between the T-shaped member and the sound and ear tubes.

45

3. In a stethoscope head-piece, a tubular soft rubber T-shaped member connecting the sound tube with the ear tubes, and a metal spring embedded in the upper portion of said T-shaped member and embracing 50 the ear tubes for holding the same in position.

4. In a stethoscope head-piece, a pair of ear tubes, a sound tube, a tubular soft rubber connecting member between the sound 55 tube and the ear tubes, a spring concealed in said connecting member and engaging the ear tubes, and means making a sound-proof connection between said connecting member and the sound and ear tubes.

60

5. In a stethoscope head-piece, a flexible tubular T-shaped member for connecting the sound and ear tubes, a stiffening member in said T-shaped member, comprising a tubular section at each side of the vertical leg of 65 the T adapted to embrace the end of the ear tubes, and a leaf spring connected to said tubular sections and extending between the same.

6. In a stethoscope head-piece, a flexible 70 tubular T-shaped member for connecting the sound and ear tubes, a stiffening member in said T-shaped member, comprising a tubular section at each side of the vertical leg of the T adapted to embrace the end 75 of the ear tubes, a leaf spring connected to said tubular sections and extending between the same, and a rigid tubular member in the vertical leg of the T and receiving the end of the sound tube between said latter 80 tubular member and the walls of said vertical leg.

85

In testimony whereof I have affixed my signature to this specification.

LOUIS H. MORIN.
